Application September 16, 1937, Serial No. 164,176

4 Claims. (CL. 113—38)

This invention relates to improvements in presses particularly adapted, though not necessarily limited to that type of presses commonly known as triple action, used in drawing metal.

In presses of this character, and particularly when a plurality of slides are employed, one of which is operable as a blank or work holder, it is necessary in order to perform the drawing, or the shaping of the work, to provide a degree or period of dwell in the blank holding slide while it is holding or gripping the work, and while another slide is imparting its operating stroke.

Heretofore the operating means for the blank holder has either been from a crank motion, or mechanism describing a circular path of movement, and in order to obtain a long dwell it has been necessary to employ a large number or series of links, the pivots of which pass through dead centers, as well as other complicated and expensive mechanism.

Even with such prior structures the amount of dwell obtained has been of comparatively short duration with respect to the 360° of rotation of the actuating shafts or gears.

It is one of the objects of the present invention to provide improved means whereby a degree of dwell of the blank or work holding slide as high as 150° or even more of a dwell can be obtained in one complete cycle of rotation of the main driving gear or shaft, and at the same time simplify the construction and reduce the amount of linkage necessary, by selecting the driving or operating point for the blank holder movement, and locating such driving or connection point of the links with an eccentric actuating strap, and which point of connection will be laterally offset with respect to the center of the eccentric, causing, when the eccentric is rotated, the center of the pin or connection to travel in an elliptical path of movement, thereby obtaining a long dwell without the use of the conventional link motion.

During such movement of the said point of connection, the period of dwell of the blank or work holder will occur on the flat or long side of the ellipse.

With this simple construction of providing an offset pin on the eccentric strap, all that is necessary to change the amount of dwell is to change the location of the center of this pin, whereas in presses of the conventional type, change of the entire linkage is necessary if the duration of dwell is required to be altered.

To the attainment of these ends and the accomplishment of other new and useful objects as will appear, the invention consists in the features of novelty in substantially the construction, combination and arrangement of the several parts, hereinafter more fully described and claimed and shown in the accompanying drawings illustrating this invention, and in which

Figure 1 is a view partly in elevation, partly in section and partly broken away of a press of this character constructed in accordance with the principles of this invention.

Figure 2 is a top plan view of Figure 1.

Figure 3 is a detail vertical sectional view taken on line 3—3, Figure 2.

Figure 4 is a view partly in elevation, partly in section and partly broken away of the mechanism for actuating the inner slide.

Figure 5 is a view similar to Figure 4 showing a portion of the mechanism for actuating the outer slide.

Figure 6 is a detail view partly in elevation, partly broken away and partly in section, showing a portion of the mechanism whereby the extended period of dwell of the inner slide is obtained, on an enlarged scale.

Figure 7 is a detail perspective view of the mechanism shown in Figure 6.

Figure 8 is a view partly in elevation, partly in section and partly broken away, showing the bed of a press, the lower slide and the mechanism for actuating the lower slide.

Figure 9 is an irregular vertical sectional view taken on line 9—9, Figure 8.

Figure 10 is a cyclograph of the movement of the slides showing the extended or long period of dwell obtained in the slides.

Figure 11 is another cyclograph of the movement of the upper slides obtainable with this mechanism.

Referring more particularly to the drawings, the press consists essentially of a bed 15, uprights 16, a hollow crown 17, secured together in any suitable manner, an outer slide 18 slidable upon guides 19 carried by the uprights, and an inner slide 20 nested with the outer slide 18 and movable in guides 21 on the outer slide, all as well known in this art.

The outer slide 18, constituting a blank or work holder, is supported by upright members 22 adjustably connected at one end to the slide, in any suitable manner and moving through suitable bearings 23, supported by the bottom of the crown 17, and which bearings are of such a length that the outer slide will be relieved of all lateral stresses exerted upon the members 22 by the actuating mechanism.

Loosely supported upon shafts 24, which shafts are laterally spaced, parallel with each other, and journaled in suitable bearings, are rocking members 25, one member being provided for each of the supporting members 22, and the members 25 are connected with the respective members 22 through the medium of links 26 pivotally connected at one end as at 27 with the members 25, and pivotally connected at their other end as at 28 with the members 22, so that when the members 25 are rocked about the shafts 24, in a man-

ner to be described, a reciprocatory movement will be imparted to the outer slide 18.

In order to obtain a period of dwell in the outer slide, suitable mechanism intermediate the members 25 and the actuating eccentric is provided, and as the actuating mechanism which is connected to each of the members 22 is the same, the description of one will apply equally as well to them all. Secured to the shaft 24 for rotation therewith is an eccentric 29, and an eccentric strap 30 encompasses the eccentric and the eccentric strap is provided with a projecting portion 31 which is offset laterally with respect to the center of the eccentric. A supporting shaft 32 arranged parallel with the shaft 24 carries a sleeve 33 mounted to oscillate about such shaft, and connected to the sleeve is an arm 34 which in turn is connected by means of a link 35 with the rocking member 25, the link 35 being pivotally connected as at 36 with the arm 34 and as at 37 with the member 25.

The sleeve 33 is provided with arms 38 (see particularly Figure 2) which are connected with the eccentric strap 30 through the medium of a link 39 one end of which is pivotally connected as at 40 to the arms 38 and the other end is pivotally connected as at 41 with the extension 31 of the eccentric strap 30.

With this construction, when the eccentric 29 is rotated in the direction indicated by the arrow in Figure 6 the eccentric strap, and particularly the portion 31 thereof, will be given a movement that the point of pivotal connection 41 between the link 39 and the portion 31 of the eccentric strap will be given an elliptical path of movement as indicated by the line 42 in Figure 6. This will rock the sleeve 33 and through the medium of the intermediate connecting members between the sleeve 33 and the member 22 will move the outer slide downwardly into engagement with the work and thence upwardly. The movement of the slide toward and into engagement with the work will occur while the pivot point 41 is traveling through the smaller arcs of the ellipse, and, after the slide has moved into engagement with the work to clamp the same, the pivot point 41 will be traveling along the long side of the ellipse, thereby producing a prolonged or extended dwell of the slide for approximately 50 150° of the 360° of rotation of the driving shaft 24 or eccentric 29.

The end 43 of the eccentric strap 30 is connected to an arm 44 by means of a pivot 45 and this arm 44 is connected to a sleeve 46 (see particularly Figure 3) that is in turn mounted upon a bearing or extension 47 of one of the eccentrics 29, and depending from the sleeve 46 is an arm 48 to which latter is pivotally connected by means of a pivot 49, a link 50. This link in turn is connected to upright members 51 (see also Figure 4) which latter are in turn adjustably connected to the inner slide 22 (see also Figure 1). The members 51 slide in extended bearings 52 which are supported by the crown 17. The bearings 52 are 65 of such a length that the members 51 will remain upright so that any lateral stress exerted upon the members 51 by the actuating mechanism for the inner slide, will not be manifested upon the inner slide 20.

70 Thus it will be seen that upon operation of the eccentric 29, the outer slide will be operated through the medium of the connection of the links between the slide and the eccentric strap at one end of the eccentric strap, and the inner 75 slide will be operated by the link mechanism

which is connected to the free end or extremity 43 of the eccentric strap.

With this construction four eccentrics will be provided and the connections between the links and the portion 31 of the eccentric strap, by the pivot 41 will operate the outer slide, one being provided adjacent each corner of the slide, while the free ends of the eccentric strap through the medium of the link connection will operate the inner slide. Each eccentric strap will be connected at one point to the outer slide and at another point to the inner slide but the points of connection between the outer and inner slides will be on opposite sides of the press.

The shafts 24 have secured thereto operating 15 gears 53 (see particularly Figures 1 and 2) which mesh with each other and meshing with one of the gears is a pinion 54 which is mounted upon a shaft 55 and on the shaft 55 is another gear 56. This gear 56 is in turn rotated by means of a 20 pinion 57 meshing therewith. The pinion 57 is driven from a motor 58. Intermediate the pinion 57 and the motor 58 is a clutch device of any desired or suitable construction which is adapted to be rendered active and inactive to cause the shafts 25 24 to be rotated or to arrest their movement. This is accomplished by actuating the clutch device 59 in any suitable manner, either manually, electrically, hydraulically or by fluid pressure (not shown). Suffice it to say that when the clutch 30 is rendered active the shafts 24 will be rotated but when the clutch is rendered inactive the shafts 24 will remain idle. Any suitable connection between the pinion 57 and the motor may be provided, such for instance as a belt drive 60 35 passing over a pulley 61 on the motor shaft and a pulley 62 which forms a part of the clutch device.

A lower slide 63 operates in the bed 15 and this slide may be actuated in any desired or suitable manner such as by means of eccentrics 64 with 40 which eccentric straps 65 co-operate. These eccentric straps are pivotally connected to uprights 66, any number of which may be provided. The uprights in turn are adjustably connected with the slide 63, as at 67, and the uprights slide 45 in extended bearings 68 so that any lateral stresses exerted upon the uprights 66 by the actuating mechanism will not be manifested upon the slide 63.

One of these uprights and eccentric driving 50 mechanisms is preferably provided in each corner of and below the bed.

Each eccentric 64, is secured to a shaft 69 and the shaft is rotated by means of a gear 70 with which a pinion gear 71 meshes. This pinion gear 55 is in turn connected with a gear 72 and the adjacent gears 72 mesh with each other. A pinion gear 73 meshes with one of the gears 72 and this pinion gear is connected to a shaft 74, the shaft in turn being connected to a clutch member 75, 60 (see particularly Figures 8 and 9). Loosely mounted upon the shaft 74 is another clutch member 76 with which the clutch member 75 co-operates. Passing over the clutch member 76 is an endless drive belt 77 which passes over a pulley 78 on the shaft 79 of a motor 80, the motor 80 being supported by a suitable bracket 81.

The clutch member 76 is continuously rotated by the motor and is mounted to freely rotate 70 upon the shaft 74 and when the clutch member 75 is inactive with respect to the clutch member 76, the shaft 74 will remain idle. When, however, the clutch members 75 and 76 are rendered active with respect to each other, the shaft 74 will be 75

rotated and this in turn will rotate eccentrics 64 to reciprocate the slide 63.

The upper slides 18 and 20 and the lower slide 63 may be operated in timed relation with each other or in any predetermined order or sequence, the operation of the slides being controlled by the respective clutch devices.

By reason of the link connection between the eccentric straps 30 and the outer slides, and by reason of the pivot 41 traveling in the elliptical path indicated by the line 42, there is procured a period of dwell in the operation of the outer slide for a greater extent, or approximately 150° with respect to the complete cycle of operation of the driving shafts, to-wit, the shafts 24, or the eccentrics 29, than has been possible with the construction heretofore provided. The period of dwell in the operation of the outer slide is diagrammatically represented in the cyclographs.

The degree of dwell of the inner slide is also indicated in cyclographs.

When it is desired to increase the period of dwell in the operation of both the inner and the outer slides, the clutch device controlling these two slides is rendered inactive at a predetermined time of the operation of the press, that is, when the slides reach the limit of their lowermost movement; that is, when the dies carried by these slides are operating upon the work, the clutch device which controls these slides is rendered inactive. In other words, the actuating mechanism for the slides 18 and 20 is disconnected from the motor so that these two slides will remain at rest while the lower slide is operating.

When it is desired to control the movement of the lower slide the clutch device which controls this slide is rendered active or inactive according to the work which the lower slide is to perform or whether it is desired to maintain the lower slide inactive.

The dwell is obtained in the outer or blank holding slide through the medium of the link connection with the eccentric strap, while the dwell of the inner slide is obtained by disengaging the clutch device and arresting the movement of the shafts 24 and eccentrics 29.

With this improved construction it will be manifest that the period of dwell of the slides is materially increased from the period of dwells which can be obtained with prior constructions, and at the same time a considerably less expensive structure is produced and the number of links has been reduced and the complicated mechanism heretofore necessary to accomplish these results has been very much simplified.

By the manipulation of the clutch devices with respect to their individual actuating mechanisms, this press may be caused to operate either as a triple or a double action press.

While the preferred form of the invention has been herein described, it is to be understood that various changes may be made in the details of construction and in the combination and arrangement of the several parts, within the scope of the claims, without departing from the spirit of this invention.

What is claimed as new is:—

1. In a press, a plurality of slides, a plurality of eccentrics, eccentric straps individual to the eccentrics, two sets of rocker members, said eccentric straps directly connected to one set of said rocker members, means forming connections between one of said sets of rocker members and one of said slides, means forming connections between the other set of rocker members and another of said slides, links pivotally connected at

one end to the other set of rocker members and pivotally connected at the other end to the eccentric straps at points offset from the center of the respective eccentrics, the said points moving in an elliptical path during operation of the eccentrics, said links being of such length that during the movement of said points about a substantial portion of its elliptical path they will pivot about their points of connection with the rocker members, whereby an extended period of dwell will be obtained in the slide.

2. In a press, a plurality of slides, a plurality of eccentrics, eccentric straps individual to the eccentrics, two sets of rocker members, said eccentric straps directly connected to one set of said rocker members, means forming connections between one of said sets of rocker members and one of said slides, means forming connections between the other set of rocker members and another of said slides, links pivotally connected at one end to the other set of rocker members and pivotally connected at the other end to the eccentric straps at points offset from the center of the respective eccentrics, the said points moving in an elliptical path during operation of the eccentrics, said links being of such lengths that during the movement of said points about a substantial portion of its elliptical path they will pivot about their points of connection with the rocker members, this portion of the elliptical path being substantially the same as the path of a radius of the link described from its point of connection with the rocker member, whereby an extended period of dwell will be obtained in the slide.

3. A press, embodying in its structure two slides, an eccentric, an eccentric strap, a rocker member, said eccentric strap connected to the rocker member, means forming a connection between said rocker member and one of the slides, a second rocker member, means forming a connection between said second rocker member and the other slide, a link pivotally connected at one end to the last said rocker member and pivotally connected at its other end to the eccentric strap at a point offset from the center of the eccentric, said point moving in an elliptical path during operation of the eccentric, said link being of such length that during the movement of said point through a portion of its elliptical path it will pivot about its point of connection with the rocker member, whereby an extended period of dwell will be obtained in the slide.

4. A press embodying in its structure two slides, an eccentric, an eccentric strap, a rocker member, said eccentric strap connected to the rocker member, means forming a connection between said rocker member and one of the slides, a second rocker member, means forming a connection between said second rocker member and the other slide, a link pivotally connected at one end to the last said rocker member and pivotally connected at its other end to the eccentric strap at a point offset from the center of the eccentric, said point moving in an elliptical path during operation of the eccentric, said link being of such length that during the movement of said point through a portion of its elliptical path it will pivot about its point of connection with the rocker member, this portion of the elliptical path being substantially the same as the radius of the link described from its point of connection with the rocker member, whereby an extended period of dwell will be obtained in the slide.

RUDOLPH W. GLASNER.

EINAR K. JOHANSEN.
